UNITED STATES PATENT OFFICE.

JOHN L. EVANS, OF JACKSON, TENNESSEE.

BASEBALL GAME.

Application filed June 13, 1922. Serial No. 568,029.

To all whom it may concern:

Be it known that I, JOHN L. EVANS, a citizen of the United States, residing at Jackson, in the county of Madison and State of 5 Tennessee, have invented new and useful Improvements in Baseball Games, of which the following is a specification.

This invention has reference to what may be termed an indoor or parlor game of baseball modeled after what is popularly known 10 as the National Game of America.

An object of the invention is to provide a baseball game of an interesting and enjoyable character which can be played at 15 home by two or more contestants, just as upon a diamond with opposing teams and with plays simulating the actual occurrence during a regular game.

An additional object is to provide a game 20 of the character specified which embodies novel means for regulating the movements and disposing of the various pieces during the playing of the game.

A further object of the invention is to 25 provide a game which can be manufactured and marketed at slight cost and which will provide enjoyment for both the young and old.

The invention consists in a novel design 30 of a game board having thereon a design of a baseball diamond, and the combination with such board of dies representing features and characters, as will be more clearly described in the following specification illustrated in the accompanying drawings and finally pointed out in the appended claims.

In the accompanying drawing, in which corresponding parts are indicated by similar reference characters:

40 Figure 1 is a plan view showing the lay-out of the diamond.

Figure 2 is a perspective view of the ball; and

Figure 3 is a perspective view of the bat.

45 Fig. 4 is a perspective view of one of the game pieces.

Fig. 5 is a similar view to Fig. 3 showing other faces.

The game is to be played upon a board 50 having thereon a diagram of a baseball diamond, as indicated at 10; the same presenting the usual pitcher's and batter's boxes, as shown, the bases of the diamond being preferably six inches apart. The players of the 55 two opposing teams may be represented by any suitable game pieces, there being nine

regular players and each team with a letter or other symbol upon each, indicating their respective positions in play. Each team may also include a number of substitute players, preferably three, that may be used as "pinch hitters" or to replace any of the regular players of the team. The teams alternately have a time at the "bat" and "in the field," the players when in the field 60 being arranged on the diamond according to their respective positions in play and when at bat having a batting order as follows: catcher, pitcher, first baseman, second baseman, third baseman, shortstop, right fielder, center fielder, and left fielder. The batters should appear in the batter's box in their regular order, unless replaced by a substitute, and to have a player bat out of his turn constitutes an out for the team at the 75 bat.

When a substitute player replaces a regular player in any game, the latter is not eligible to play at any subsequent period during such game, and can only be used 80 when beginning another game. The batters may be placed either to the left or right of the home plate as desired, thus signifying either a right or a left hand batter.

The game is preferably played by two 85 parties who represent the competing teams, and who decide by agreement or otherwise, which will go to the bat first. The movements of the players are controlled by special game pieces, such as indicated at 11 and 12 90 respectively, the former being hereafter referred to as the "ball" and the latter as the "bat." The ball is preferably a cube having colored sides, two surfaces being white; three, blue; and one, red. The ball 95 is used by the party whose team is in the field, and its various colored sides signify various actions of the pitcher during the playing of the game. White and blue signify throws to the batter, the former denoting a ball and the latter, a strike, while red signifies that the pitcher has made a throw 100 to the base. The bat is used by the party representing the team at the bat, and is an octahedron having yellow and two blue 105 surfaces being marked 0, 1, 2, 3, and 4, respectively. The marked and colored surfaces signify the action of the batter, yellow denoting a foul, blue denoting a strike, and 0 denoting that the batter has hit the 110 ball and is out. Numerals 1, 2, 3, and 4, indicate respectively a one base hit, a two

base hit, a three base hit and a home run.

At the start of the game the party "at the bat" places the catcher in one of the batter's boxes and the party in the field then

5 tosses the "ball" into the "pitcher's box."

If desired, the piece may be shaken and tossed from a dice cup, and the color of the side up indicates what has been thrown. If white, it signifies that the pitcher has

10 thrown a ball, and if blue, it signifies that the pitcher has thrown a strike. If pitcher throws four balls the batter is then entitled to first base, and the next player in order takes his turn at bat. Only when a pitcher

15 throws a strike, that is, when the side up is blue, does the party at bat act, at which time he shakes the bat from the cup, the mark or color on the top side indicating the result of the batting. If the top pre-

20 sentents the numeral 1, the batter is credited with a base hit; if numeral 2 is disclosed he is credited with a 2 base hit, and so on, all runners occupying bases when a hit is made being moved around according to the

25 number of bases indicated by the hit. However, each runner or runners should be moved up to their proper positions before moving the batter, since if the batter and the runner or two runners occupy the same

30 base at one time, the runner nearest home plate is considered out and removed from the base. When the yellow side of the bat is uppermost, it indicates the batter has hit a foul, which will count as a strike, until

35 two are called; and when a blue side is uppermost, it signifies that the batter has failed to hit, the pitcher being, therefore, credited with a strike, three of which puts the batter out. Should one party in the

40 field drop the ball during his inning in the field and it should fall outside the foul line while there are one or more runners occupying the bases, the runner nearest home is given a stolen base and moved up a base.

45 Likewise if he drops the ball and permits it to get beyond the foul line when there are no runners on base, it signifies that the batter has been hit with the ball delivered by the pitcher and is entitled to be moved to

50 first base. When the top side of the ball dropped within the diamond presents a red color, it denotes that the pitcher has made a throw to the base, as before explained, and in the event that the bases are unoccupied

55 at the time, it counts for nothing. However, if one or more bases are occupied by runners, it signifies that the runner nearest home plate has been caught on an attempted steal and is out.

60 When three outs have been obtained on the side at bat, the said side is retired and takes its position in the field while the other team goes to bat. The teams thus alternate between the bat and field until nine innings have been played, the team making the

greatest number of runs winning the game.

From the foregoing it is thought that the advantages and novel features of the invention can be readily understood and that further description is not required. 70

Although in the foregoing, I have described and illustrated the preferable design of board and code of play forming the subject-matter of this invention, it is to be understood that slight changes as to colors, 75 design, and rules governing the game may be utilized without departing from the spirit of the invention or evading the appended claims.

Without enumerating variations and 80 equivalents, what I desire protected by Letters Patent is:

1. A baseball game comprising a primary die having means thereon for indicating various acts performed by the pitcher, and a 85 second die having means thereon for indicating various acts performed by the batter, the means on the primary die determining the point in the game when the secondary die is to be utilized, the use of the secondary die being subsequent to and controlled by the use of the primary die. 90

2. A baseball game comprising a primary die having various colors thereon for indicating different acts performed by the 95 pitcher, and a second die having means thereon for indicating various acts performed by the batter, the various colors on the primary die determining the point in the game when the secondary die is to be utilized, the use of the secondary die being 100 subsequent to and controlled by the use of the primary die.

3. A baseball game comprising a primary die having means thereon for indicating various acts performed by the pitcher, and a second die having various colors thereon for indicating different acts performed by the batter, the means on the primary die determining the point in the game when the secondary die is to be utilized, the use of the secondary die being subsequent to and controlled by the use of the primary die. 105

4. A baseball game comprising a primary die having means thereon for indicating various acts performed by the pitcher, and a secondary die having numbers thereon for indicating various acts performed by the batter, the means on the primary die determining the point in the game when the secondary die is to be utilized, the use of the secondary die being subsequent to and controlled by the use of the primary die, the numbers on the secondary die determining the play values. 115

5. A baseball game comprising a primary die having means thereon for indicating various acts performed by the pitcher, and a secondary die having different colors and 120

125

130

- numbers thereon for indicating various acts performed by the batter, the means on the primary die determining the point in the game when the secondary die is to be utilized, the use of the secondary die being subsequent to and controlled by the use of the primary die, the different colors and numbers on the secondary die determining the play values.
- 10 6. A baseball game comprising a primary die having different colors thereon for indicating various acts performed by the pitcher, and a secondary die having different numbers thereon for indicating various acts performed by the batter, the colors on the primary die determining the point in the game when the secondary die is to be utilized, the use of the secondary die being subsequent to and controlled by the use of the primary die, the different numbers on the secondary die determining the play values.
- 15 7. A baseball game comprising a primary die having different colors thereon for indicating various acts performed by the pitcher, and a secondary die having different colors and numbers thereon for indicating various acts performed by the batter, the different colors on the primary die determining the point in the game when the secondary die is to be utilized, and the use of the secondary die being subsequent to and controlled by the use of the primary die.
- 20 8. A baseball game comprising a board inscribed with the representation of a baseball diamond, two sets of game pieces for representing, respectively, the team at the bat and the team on the field, a primary die having means thereon for indicating various acts of the pitcher, and a secondary die having means thereon for indicating various acts of the batter, the means on the primary die determining the point in the game when the secondary die is to be utilized, the use of the secondary die being subsequent to and controlled by the use of the primary die.
- 25 9. A baseball game comprising a board inscribed with the representation of a baseball diamond, two sets of game pieces for representing, respectively, the team at the bat and the team on the field, a primary die for indicating various acts performed by the pitcher, said die having different colors thereon, indicating, respectively, a strike, a ball, and a throw to one or the other of the bases, and a secondary die for indicating different acts performed by the batter, said secondary die having thereon different colors indicating respectively, a foul strike and missed strikes, and a series of numbers va-
- rying from 0 to 4, and indicating in order, an out, a 1 base hit, a 2 base hit, a 3 base hit and a home run, the indicia on the primary die also determining the point in the game when the secondary die is to be utilized, the use of the secondary die being subsequent to and controlled by the use of the primary die.
- 30 10. A baseball game comprising a board inscribed with the representation of a baseball diamond, two sets of game pieces representing, respectively, the team at the bat and the team in the field, a primary and a secondary die for indicating various plays of the game and controlling the movement of the game pieces representing the men on bases and at bat, the primary die having means thereon for indicating various acts performed by the pitcher, the secondary die having means thereon for indicating various acts performed by the batter, the means on the primary die determining the point in the game when the secondary die is to be utilized, and the use of the secondary die being subsequent to and controlled by the use of the primary die.
- 35 11. A baseball game comprising a primary die having markings thereon for indicating different acts performed by the pitcher, and a secondary die of dissimilar configuration to the primary die and having a number of markings in excess of those on said primary die for indicating various acts performed by the batter, the use of the secondary die being always subsequent to and controlled by the use of the primary die, but not always in alternate order, the markings on the primary die determining the alternate order.
- 40 12. A baseball game comprising a primary die having indicia thereon for indicating different acts performed by the pitcher, and a secondary die differing in configuration from the primary die and having indicia thereon for indicating various acts performed by the batter, the indicia on the primary die determining the point in the game when the secondary die is to be utilized, the indicia on the said primary and secondary dies is also different to determine the game moves, the use of the secondary die being always subsequent to and controlled by the use of the primary die, but not necessarily in alternate order, the alternate order being determined by the indicia on the primary die.
